UNITED STATES PATENT OFFICE.

ABRAHAM PFLANTZER, OF NEW YORK, N. Y.

DESIGN FOR A DENTAL FOUNTAIN CUSPIDOR.

Application filed February 20, 1923. Serial No. 5,219. Term of patent 14 years.

To all whom it may concern:

Be it known that I, ABRAHAM PFLANTZER, a citizen of the United States, and a resident of the city of New York, in the county of New York and State of New York, have invented a new, original, and ornamental Design for a Dental Fountain Cuspidor, of which the following is a specification, reference being had to the accompanying drawing, forming a part hereof.

Fig. 1 is a side elevation; and
Fig. 2 is a front elevation, looking at
Fig. 1 from the right.

I claim:

The ornamental design for a dental fountain cuspidor, as shown.

ABRAHAM PFLANTZER.

Witnesses:

JOHN D. MORGAN,
GLADYS VAN LOON.
